United States Patent Office

Des. 198,975

Patented Aug. 25, 1964

198,975

BADGE

Lucas C. Holmes, 324½ W. 76th St., Los Angeles, Calif.

Filed Oct. 7, 1963, Ser. No. 76,876

Term of patent 14 years

(Cl. D29—2)

FIG. 1.

FIG. 2.

The drawing has been lined for color and the dominant features of the design are shown in solid lines.

I claim:

The ornamental design for a badge as shown and described.
